BY Campbell & Co., ATTY'S.

UNITED STATES PATENT OFFICE.

WILLIAM ALEX WILLIAMSON, OF NEWARK, NEW JERSEY.

DESIGN FOR A SASH HOOK OR LIFT.

SPECIFICATION forming part of Design No. 19,170, dated June 18, 1889.

Application filed May 20, 1889. Serial No. 311,474. Term of patent 14 years.

To all whom it may concern:

Be it known that I, WILLIAM ALEX WILLIAMSON, a citizen of the United States, residing at Newark, in the county of Essex and State of New Jersey, have invented and produced a new and original Design for Sash Hooks or Lifts, of which the following is a specification, reference being had to the accompanying drawings, and to letters of reference marked thereon, which form a part of this specification.

This design is composed of two distinct elements, which are used in combination to insure the beauty of the article. These consist, first, of two wires formed and joined into a twist, and, second, formed above the twist into a loop or hook portion and below the twist at the free ends of the wires into rings or eyes, the beauty and effect of this design being due to these features, which together form the new and original design, and without which it cannot be produced.

In the said drawings herewith accompanying, Figures 1, 2, and 3 represent front elevations of my new and original design, illustrating more particularly the different arrangements of the rings or eyes at the free ends of the wires below the twist and the arrangement of the loop above the twist of the wires forming the sash hook or lift. Fig. 4 is a side elevation of my design.

As indicated in Figs. 1, 2, and 3, to which reference is made in the above, my design for a sash hook or lift presents in front elevation two wires a a' , of any desirable cross-section,

which join and form a twist b , which presents the same appearance on all sides, and at the free ends of the wires, below the twist, the wires are formed into the rings or eyes c c' . The said eyes c c' may project at equal distances on opposite sides of the wires a a' , as in Fig. 1, or they may project toward each other, as in Fig. 3, or they may be formed directly underneath the wires a a' , as in Fig. 2, so that a line drawn through the axes of the wires a and a' , respectively, and prolonged will pass directly through the centers of the circular eyes c and c' . Above the twist the wires present the appearance of a loop d in front elevation and a hook d' in side elevation, and, as has been already stated in the above, the wires below the twist form the circular eyes or rings c c' when viewed in front elevation.

What I claim, and desire to secure by Letters Patent, is—

The design for a sash hook or lift herein shown and described, the same consisting of two wires a a' , twisted at b , and forming a loop d in front elevation and a hook d' in side elevation above the twist, and eyes or rings c c' below the twist circular or round in front elevation.

In testimony that I claim the invention set forth above I have hereunto set my hand this 17th day of May, 1889.

WILLIAM ALEX WILLIAMSON.
